MULTICOLOR PENCIL

Willy Schmieglitz, Berlin-Wilmersdorf, Germany

Application April 7, 1949, Serial No. 93,512

12 Claims. (Cl. 120—14.5)

1

My invention relates to a multi-color pencil and, more particularly, to a pencil of the type in which one lead may be elected from a plurality of leads and moved to operative position by means of a slidably mounted lead-holder, the lead previously occupying the operative position being coincidentally and automatically returned to retracted position.

The objects of my invention are to simplify the mechanism of a multi-color pencil of this kind; to so devise the mechanism that the lead elected for operation at any time and moved to its working position will substantially coincide with the axis of the pencil, to create a multi-color pencil having its actuating knobs located near the rear end of the pencil, as is desirable for easy manipulation; and to provide a multi-color pencil of a simple and rugged structure that lends itself to cheap mass production and is subject to wear to a lesser degree than similar designs known prior to my invention.

In prior multi-color pencils as available on the market, knobs for the manipulation extending outwardly from the lead-holders through slots provided in the casing assume a position intermediate the ends of the pencil. This intermediate location is undesirable. Moreover, these prior pencils are complicated, unreliable in operation and expensive in manufacture. As will appear from a detailed description of my invention following hereinafter, my improved multi-color pencil is free from such disadvantages and, owing to the position of the actuating knobs near the rear end, permits of a simple and rapid manipulation by the fingers of the same hand that is holding the pencil.

A preferred embodiment of my invention is illustrated in the accompanying drawing, Fig. 1 showing a longitudinal section of the improved multi-color pencil,

Fig. 2 being a plan view on a smaller scale disclosing a modification,

Figs. 3, 5 and 7 being diagrammatic representations showing one of the lead-holders in its retracted position, in an intermediate position, and in its projected position relative to the latch and the other basic elements of the pencil,

Figs. 4, 6 and 8 being lateral views of the lead-holder and of the rotary latch in upper, middle, and lower position, respectively,

Fig. 9 is a partial section taken along line 9—9 of Fig. 1, the rotary latch being shown in elevation,

Fig. 10 is a bottom view of the rotary latch of Fig. 9, and

2

Fig. 11 is a cross-section of the core member taken along line 11—11 of Fig. 1;

A cylindrical or hexagonal sleeve 1 tapering towards its muzzle 21 affords a seat for a tightly inserted substantially cylindrical core 2 and constitutes a tubular casing for a plurality of lead-holders which are individually movable from a resting position within the casing 1 to a projected position shown in Fig. 7. Each of the lead-holders is composed of a flat actuating bar 6, of a sleeve adapted to be loaded with a lead, such as 22, and of a hinge 7 connecting said sleeve to the actuating bar 6. As will appear from Fig. 1 the element referred to hereinabove as a sleeve is in its turn composed of an upper sheet metal member 8 having a U-shaped cross section and of a lower tubular element 9 accommodating the lead 22. The element 9 has a collar 23 at its upper end which is embraced by and 10 rotatably journaled in the member 8 and held thereby against axial displacement. The lower end of the tubular element 9 is knurled so that it may be easily turned about its axis when projecting from the muzzle 21. Such rotation causes 15 an axial movement of the push rod 10 inside of the tube 9 to impart the required feed motion to the lead 22 from time to time to compensate for the wear thereof.

As will appear from Fig. 11, the core 2 is provided with longitudinal slots 20 extending in axial planes and slidably accommodating the actuating bars 6. The upper ends of the latter have outwardly projecting arms extending through longitudinal slots 25 of the casing 1 and bearing knobs 19 for manual displacement from the retracted position shown in Figs. 1 and 3 to the projected position shown in Fig. 7.

As stated above it is one of the objects of my invention to so design the various elements that, owing to their shape and co-ordination, the sleeve 8, 9 when in projected position, will substantially coincide with the axis of the casing 1.

To this end, the grooves 20 are so shaped as to guide each actuating bar 6 along a path converging towards the axis of the casing, as illustrated in Figs. 3, 5 and 7 showing that the hinge 7 moves from an eccentric retracted position towards the axis until substantially coinciding therewith, when arriving in the projected position of Fig. 7.

In the embodiment illustrated, this effect is obtained by the bottom of the grooves 20 being convex longitudinally and the bars themselves being curved accordingly for guidance along 45 curved paths.

Owing to its truly axial alignment, the tubular element 9 will be firmly held by the muzzle 21, when projecting therethrough, without any objectionable lost motion.

While in the embodiment shown in Fig. 1, the casing 1 is illustrated as extending over the core 2 up to the top thereof being provided with slots 25 affording the required freedom of movement to the actuating bars 6, I may modify the design by terminating the casing 1 at the line 26 shown in Fig. 2 thus leaving the upper section of core 2 bare. In this modification, casing 1 need not be provided with any slots. In either case the core may have a pressed fit in the casing 1 to save the cost of additional connecting means.

The core 2 has an axial bore 17' dimensioned to render it fit for the accommodation of reserve leads 17. The upper end of the core 2 has external threads and a shoulder affording a seat for the upper off-set extension 4 of a clip held in position by a knob 5. A cap 3 screwed on the core member 2 constitutes a cover of the magazine 17'.

Helical springs 11 having their lower ends attached to the lead-holders and their upper ends to a spider 12 attached to the core 2 by an axial bolt 27 serve to keep the lead-holders in the resting position in which their upper ends engage member 4.

I shall now describe another important feature of my invention same being the provision of new and simplified means for arresting any lead-holder in its projected position shown in Fig. 7 once it has been manually shifted thereto.

Rotatably mounted on the lower end of the axial bolt 27 projecting from the core member 2, there is a star shaped latch 13 having upturned arms provided with slanting edges 14 as shown in Fig. 9. Notches 18 are formed between the arms. This latch 13 is normally held in the position shown in Fig. 9 by a U-shaped leaf spring 16 which is encased within a cavity provided in the bottom of the core member 2 and has one of its arms projecting downwardly through a hole 28 (Figs. 1 and 10) in member 13. This spring is so mounted as to urge its extended arm into contact with the left hand wall of the cavity as shown in Fig. 9. This arm, however, may be deflected by an oscillation of the latch 13 about the axial bolt 27 into a position indicated in Fig. 9 by dotted lines. The radial arms of the latch 13 extend normally into the paths of the actuating bars 6 or, more specifically, into the path of downwardly facing shoulders 29 provided in said arms by inner recesses 15 therein. When one of the actuating bars 6 is shifted downwardly by manual actuation of its knob 19, its shoulder 29 engages the face of the slanting edge 14 thus oscillating the latch 13 until the bar 6 is disposed in a notch 18. Continued downward motion of the bar 6 brings an upwardly facing shoulder 30 thereof beneath the latch 13. When this happens, latch 13 will be re-set to its initial position by the spring 16 and will consequently lock and arrest the lowered bar 6 upon manual release of the latter. The shoulder 30 is provided by another inner recess 15' of each bar 6.

It will be appreciated that the oscillation of the star-shaped latch 13 by engagement thereof with the shoulder 29 of any selected lead-holder will cause the coincidental release of any previously arrested lead-holders by the sliding of shoulder 30 thereof along slanting edge 14 into notch 18 and the consequent return thereof by its spring 11 to resting position.

As will appear from the above description, the core 2 carrying the single latch 13 and the spider 12 for attachment of the springs 11 and provided with the guiding grooves 20 for the lead-holders constitutes a single self-contained unit therewith retaining its integrity even after disassembly from the casing 1. This facilitates the assembly or any later repair work.

While I have described my invention by reference to a pencil having four lead-holders for leads of different colors, it is obvious that I may embody the same principle in pencils having two, three, five or more lead-holders.

Moreover, I wish it to be clearly understood that my invention is in no way limited to the details shown in the drawings and described herein above but is capable of numerous modifications within the scope of the appended claims.

What I claim is:

1. In a multi-color pencil, the combination comprising a plurality of lead-holders, a tubular casing therefor, means for slidably mounting each of said holders to be individually movable from a retracted position within said casing to a projected position, a retracting spring connected to each of said lead-holders, and a single latch mounted within said casing and co-operatively co-ordinated to each of said holders at the inner side thereof and adapted, upon movement of any one of them into projected position, to engage and to arrest same and to be tripped coincidentally with said movement for release of any previously projected holder and for consequent re-setting of the latter by one of said springs.

2. In a multi-color pencil, the combination comprising a plurality of lead-holders, a tubular casing therefor, each of said holders being provided with two spaced and oppositely facing shoulders, means for slidably mounting each of said holders to be individually movable from a retracted position within said casing to a projected position, a retracting spring connected to each of said lead-holders, and a single star-shaped latch centrally mounted within said casing for oscillation about the axis thereof and co-operatively co-ordinated to each of said holders and adapted, upon movement of any one of them to projected position, to engage one of the two shoulders of said projected holder to thereby arrest same and to be tripped by the other one of its two shoulders coincidentally to said movement for release of any previously projected holder and for consequent re-setting of the latter by one of said springs.

3. In a multi-color pencil, the combination comprising a plurality of lead-holders each composed of an actuating bar and of a sleeve adapted to be loaded with a lead, each of said actuating bars being formed with a locking shoulder and an operating shoulder facing opposite thereto, a tubular casing for said lead-holders, means for slidably mounting each of the latter to be individually movable from a retracted position within said casing to a projected position, a retracting spring connected to each of said lead-holders, a single star-shaped latch centrally mounted within said casing for oscillation about the axis thereof having radial arms normally extending into the paths of said actuating bars and having slanting faces for engagement by an operating shoulder of said bars, and a restoring spring for said latch adapted to urge the latter to snap behind the locking shoulder of the actuating bar of any projected lead-holder, whereby any lead-holder on movement from its retracted position

into its projected position will trip said latch for release and restoration of any previously projected lead-holder and will then be locked in projected position until another one of said holders will be projected.

4. In a multi-color pencil, the combination comprising a plurality of lead-holders, a tubular casing therefor, a core coaxially connected with said casing and having longitudinal grooves slidably guiding said lead-holders for individual movement from a retracted position within said casing to a projected position, a retracting spring connected to each of said lead-holders, and a single latch mounted on said core and each lead holder including means to operate said latch and means cooperating with said latch whereby said latch is co-operatively co-ordinated to each of said holders and adapted, upon movement of any one of them projected position, to engage and to arrest same and to be tripped coincidentally to said movement for release of any previously projected holder and for consequent re-setting of the latter by one of said springs.

5. In a multi-color pencil, the combination comprising a plurality of lead-holders each composed of an actuating bar and of a sleeve adapted to be loaded with a lead, each of said actuating bars being formed with a locking shoulder and an operating shoulder facing opposite thereto, a tubular casing for said lead-holders, a core coaxially connected with said casing and having longitudinal grooves slidably guiding said actuating bars for individual movement of said lead-holders from a retracted position within said casing to a projected position, a retracting spring connected to each of said lead-holders, a single star-shaped latch centrally mounted on said core within said casing for oscillation about the axis thereof having radial arms normally extending into the paths of said actuating bars and having slanting faces for engagement by an operating shoulder of said bars, and a restoring spring for said latch adapted to urge the latter to snap behind the locking shoulder of the actuating bar of any projected lead-holder, whereby any lead-holder on movement from its retracted position into its projected position will trip said latch for release and restoration of any previously projected lead-holder and will then be locked in projected position until another one of said holders will be projected.

6. In a multi-color pencil, the combination comprising a plurality of lead-holders, a tubular casing therefor, and a core coaxially connected with said casing and having longitudinal grooves extending in radial planes of said core, each lead-holder being composed of an actuating bar, of a sleeve adapted to be loaded with a lead, and of a hinge connecting said sleeve to said bar, said actuating bars being slidably guided within said grooves for individual movement of said lead-holders from a retracted position within said casing to a projected position in which the loaded end of said sleeve projects out of said casing, said grooves being shaped to guide each actuating bar along a path converging towards the axis of the casing so that the hinge of a lead-holder, when the latter is projected, is substantially positioned on the axis of said casing.

7. In a multi-color pencil, the combination comprising a plurality of lead-holders, a tubular casing therefor, and a core co-axially connected with said casing and having longitudinal grooves extending in radial planes of said core, each

lead-holder being composed of an actuating bar, of a sleeve adapted to be loaded with a lead, and of a hinge connecting said sleeve to said bar, said actuating bars being slidably guided within said grooves for individual movement of said lead-holders from a retracted position within said casing to a projected position in which the loaded end of said sleeve projects out of said casing, said actuating bars and said grooves being so curved as to guide each actuating bar along a curved path converging towards the axis of the casing so that the hinge of a lead-holder, when the latter is projected, is substantially positioned on the axis of said casing.

8. In a multi-color pencil, the combination comprising a plurality of lead-holders, a tubular casing therefor, a core co-axially connected with said casing and having longitudinal grooves extending in radial planes of said core, each lead-holder being composed of an actuating bar, of a sleeve adapted to be loaded with a lead, and of a hinge connecting said sleeve to said bar, said actuating bars being slidably guided within said grooves for individual movement of said lead-holders from a retracted position within said casing to a projected position in which the loaded end of said sleeve projects out of said casing, said grooves being shaped to guide each actuating bar along a path converging towards the axis of the casing so that the hinge of a lead-holder, when the latter is projected, is substantially positioned on the axis of said casing, and a single latch mounted on said core and each lead holder including means to operate said latch and means cooperating with said latch whereby said latch is co-operatively co-ordinated to each of said holders and adapted, upon movement of any one of them into projected position, to engage and to arrest same and to be tripped coincidentally to said movement for release of any previously projected holder and for consequent re-setting of the latter by one of said springs.

9. In a multi-color pencil, the combination comprising a plurality of lead-holders, a tubular casing therefor, a core co-axially connected with said casing and having longitudinal grooves extending in radial planes of said core, each lead-holder being composed of an actuating bar formed with a locking shoulder, and an operating shoulder facing opposite thereto of a sleeve adapted to be loaded with a lead, and of a hinge connecting said sleeve to said bar, said actuating bars being slidably guided within said grooves for individual movement of said lead-holders from a retracted position within said casing to a projected position in which the loaded end of said sleeve projects out of said casing, said grooves being shaped to guide each actuating bar along a path converging towards the axis of the casing so that the hinge of a lead-holder, when the latter is projected, is substantially positioned on the axis of said sleeve a retracting spring connected to each of said lead-holders, a single star-shaped latch centrally mounted on said core within said casing for oscillation about the axis thereof having radial arms normally extending into the paths of said actuating bars and having slanting faces for engagement by an operating shoulder of said bars, and a restoring spring for said latch adapted to urge the latter to snap behind the locking shoulder of the actuating bar of any projected lead-holder, whereby any lead-holder on movement from its retracted position into its projected position will trip said

latch for release and restoration of any previously projected lead-holder and will then be locked in projected position until another one of said holders will be projected.

10. In a multi-color pencil, the combination comprising a plurality of lead-holders, a tubular casing therefor, a core co-axially connected with said casing and having longitudinal grooves slidably guiding said lead-holders for individual movement from a retracted position within said casing to a projected position, re-setting springs anchored to said core and connected to said lead-holders, a single latch mounted on said core and each lead holder including means to operate said latch and means cooperating with said latch whereby said latch is co-operatively co-ordinated to each of said holders, and a spring carried by said core and engaging said latch causing the same, upon movement of any lead-holder into projected position, to engage and to arrest same, said latch being adapted to be tripped co-incidentally to said movement for release of any previously projected holder and for subsequent re-setting of the latter by one of said re-setting springs.

11. In a multi-color pencil, the combination comprising a plurality of lead-holders, a tubular casing therefor, a core co-axially connected with said casing and having an axial bore for the accommodation of reserve leads and formed with longitudinal grooves slidably guiding said lead-holders for individual movement from a retracted position within said casing to a projected position, re-setting springs anchored to said core and connected to said lead-holders, a single latch mounted on said core and each lead holder including means to operate said latch and means cooperating with said latch whereby said latch is co-operatively co-ordinated to each of said holders, and a spring carried by said core and engaging said latch causing the same, upon

movement of any lead-holder into projected position, to engage and to arrest same, said latch being adapted to be tripped co-incidentally to said movement for release of any previously projected holder and for subsequent re-setting of the latter by one of said re-setting springs.

12. In a multi-color pencil, the combination comprising a plurality of lead-holders, a tubular casing therefor having longitudinal slots, a core co-axially connected with said casing and having longitudinal grooves slidably guiding said lead-holders for individual movement from a retracted position within said casing to a projected position in which the lead-holder projects from one end of said casing, said lead-holders being provided with manually operable projections extending from said casing through said slots and positioned at the other end of said casing when in retracted position, re-setting springs anchored to said core and connected to said lead-holders, a single latch mounted on said core and each lead holder including means to operate said latch and means cooperating with said latch whereby said latch is co-operatively co-ordinated to each of said holders, and a spring carried by said core and engaging said latch causing the same, upon movement of any lead-holder into projected position, to engage and to arrest same, said latch being adapted to be tripped co-incidentally to said movement for release of any previously projected holder and for subsequent re-setting of the latter by one of said re-setting springs.
